COIL WINDING DIE

Sten Wadsten, Bloomfield, N. J., assignor to Westinghouse Lamp Company, a corporation of Pennsylvania

Original application December 28, 1929, Serial No. 417,187. Divided and this application October 15, 1931. Serial No. 568,953

2 Claims. (Cl. 153—65)

The present invention relates to an improvement in machines for helically winding a filamentary wire as shown and described in Patent No. 1,670,499, May 22, 1928, to John W. Eckstedt and relates more particularly to a coil-winding die for use in such machines, and is a division of my copending application Serial No. 417,187, filed December 28, 1929.

In the above-mentioned patent a machine is shown for coiling a fine hair-like wire to a helical form in the absence of a mandrel, and particularly for the production of lengths of coiled wire to serve as filaments for incandescent electric lamps. The said machine comprises mechanism for moving a wire through a given path by tangential engagement with a pair of oppositely disposed driving rollers which propel the wire endwise into a cavity die which is so constructed that the wire issues therefrom in the form of a continuous helix. Means are provided for cutting the helix into sections of proper lengths to constitute filaments for incandescent electric lamps.

The die is so arranged that the cavity is positioned to receive the wire from the driving rolls, the bottom of the cavity being inclined or grooved so that the wire is bent into a succession of coils which pass over a lip or separator member at the edge of the cavity. The successive turns of the coil or helix which issues from the die are consequently spaced a given distance apart and the helix is, therefore, provided of a certain diameter and pitch depending upon the dimensions of the spacer member and the radius of curvature of the effective surface of the cavity as well as the position of the die with respect to the driving rolls.

In the manufacture of coiled filamentary bodies which serve as electrical resistance elements when used as lamp filaments, it is essential to exercise extreme accuracy in the formation of the coils, since each filament or coiled section must be made in accordance with specified dimensions so that each coiled section will have a length of wire therein equal to the succeeding coiled section. Furthermore, the diameter of the coil as well as the spacing or pitch of the turns of the coil must be uniform.

The dimensions of the diameter and the proportions of the coiled sections vary for lamps of different wattage, and the data relating to such dimensions and proportions is known as the "rating" so that a coiled section for a given rating must be made in accordance with a predetermined set of dimensions. For example, a filament for a 60 watt 115 volt lamp must con-

tain a length of wire of 517 mm., it must have a diameter of .0108 inch and the coiled section must contain 398 turns per inch. The diameter of the wire also varies in filaments of different wattage lamps, and the diameter of the wire of a coiled filament of a 60 watt lamp is preferably .00187 inch.

It will be obvious that in order to produce a lamp filament and hold the coil formation to the required proportions and dimensions it is necessary to accurately form the coil-winding die and to provide accurately adjustable means for holding the said die in a given relation to the path of movement of the wire thereto. In the above-mentioned patent a coil-winding die is shown and described as preferably consisting of an extremely hard material such as a diamond. A diamond die, although having indefinite life, is difficult to produce and owing to variations in the properties of a diamond, it is very often brittle to the extent that portions of the coil-winding lip are broken off rendering the die inoperative for the purpose intended.

As set forth in the said patent the coil-winding die may be constructed from hardened steel, but inasmuch as the wire passing over the die results in excessive wear, it is necessary to replace the steel die at shorter intervals than is necessary with a diamond die. Ordinarily the replacement of one die for another would offer a considerable disadvantage since when applying a die into position for the winding of a coiled filament, it is necessary to adjust the die in several planes until the cavity is accurately located in such position that the diameter and pitch of the coil produced will be in accordance with the data supplied for the rating of the particular lamp for which the filament is to be used.

When using a diamond die, the die remains in the machine for such a long period that the amount of labor and inconvenience involved in a change from one die to another is negligible. A steel die, although easier to produce, must be changed at comparatively short intervals and the advantage given by the facility accompanying the production of the die is reduced by the time and labor involved in replacing the same.

It will further be understood in order to wind fine filamentary wire to helical form in accordance with given dimensions, it is necessary to exercise considerable care as above mentioned in accurately locating the die cavity. When it is necessary, therefore to change the die owing to wear, difficulty is encountered in replacing a new die in exactly the same position as that previously occupied by the removed die.

In my copending application Serial No. 242,715, filed December 27, 1927, for adjustable holder for coil-winding dies, apparatus is shown wherein a die may be made of steel while positioned in a holder and so arranged that the die when finished may be inserted into the coil-winding machine in exactly the same position as occupied by a die which was produced by moving a matrix against a soft-metal die blank and compressing the material of the blank to form a die cavity. Although this method is satisfactory it requires a time interval and necessitates considerable care as well as the use of a certain amount of apparatus.

An object of the invention is to provide a coil-winding die of vitreous material.

Another object of the invention is to provide a coil-winding die having a hard smooth glassy surface.

Other objects and advantages of the invention will be more fully understood as the description proceeds.

In accordance with the present invention a coil-winding die is produced by moving a matrix into contacting relation with a die blank consisting of a vitreous material such as glass, while the said blank is in a plastic condition. In practicing the invention a coil-winding die is made, for example, for the formation of filaments for 40 watt lamps. This die may be made of steel or other hard material and adjusted in a holder in the machine until it is in the exact position to wind coils for the rating required.

While in its adjusted position in the holder it is moved into contact with the end of a matrix blank and forced thereagainst until an impression of the end of the die is formed in the matrix blank thus producing a matrix member.

This matrix member is then held in a given position and a die rod having a tip consisting of a vitreous material is positioned for movement into contact with the matrix. The vitreous material may be heated by a fine pointed flame until its exposed portion is in a plastic state at which time it may be moved into contact with the matrix so that the vitreous or die portion of the die blank is formed to constitute a cavity die and ready to be positioned in a coil-winding machine.

By reason of the present method a die may be produced in a rapid and efficient manner so that if during the winding of a quantity of coiled filaments it becomes necessary to renew the die, such operation may be accomplished with a minimum loss of time.

The invention will be more fully understood by reference to the accompanying drawing in which:

Fig. 1 shows a portion of a coil-winding machine partly in section with the coil-winding die in position.

Fig. 2 is a side elevational view showing apparatus for moving a die blank in contact with a matrix for a die-forming operation.

Fig. 3 is an enlarged view of a master die and a matrix member in contact to form the wire-bending cavity in a matrix.

Fig. 4 is a view showing the master die and matrix after the latter has received its wire-bending cavity.

Fig. 5 is a side elevational view of a portion of a matrix member partly in section.

Fig. 6 is a top end view of a matrix member showing the die-forming cavity.

Fig. 7 is a side elevational view partly in section showing a die blank with a die cavity formed in a vitreous portion at its end.

Fig. 8 is an end view of the die shown in Fig. 7, and

Fig. 9 is an enlarged fragmentary cross-sectional view showing the formation of a coil-winding die with a portion of a coiled wire.

Although the present invention may be practiced to produce a cavity die for use in coil-winding machines where adjustment is necessary, it is preferable to practice the invention for producing a die in a predetermined position with respect to a machine element for application to a coil-winding machine.

Fig. 1 shows a portion of a coil-winding machine comprising a holder 10 hinged at 11 to a spindle 12 which spindle is journaled in a suitable bearing on the body of a coil-winding machine. By reason of the pivot 11 and the spindle 12 it is possible to move the casing 10 in a vertical and a horizontal plane and adjust a die 13 with relation to wire driving rollers or rolls 14 and 15 which propel a wire 16 against the die 13. The die may comprise a die rod 17 and since it is essential to provide a more accurate adjustment of the die than may be accomplished by the above-mentioned vertical and horizontal adjustment, a sleeve 18 is provided to receive the die rod 17 which sleeve is fitted in a suitable bore 19 in the casing 10.

The sleeve 18 in which the die or die rod is positioned may be termed a die sleeve or collar and a set-screw 21 is provided to engage a notch or depression 22 in the die rod to hold it in a predetermined relation to the sleeve. An adjustment of the die rod about its longitudinal axis may be obtained by a rotary movement of the sleeve 18. For this purpose the sleeve is provided with a yoke 23 having a split head 24 by means of which a clamping screw 25 secures the yoke to the said sleeve 18. Arms 26 and 27 extend downwardly from the yoke and are positioned on opposite sides of a control arm 28 integral with the casing 10, set-screws 29 and 30 passing through threaded apertures in the arms serve to permit an adjustment of the yoke with a consequent adjustment of the sleeve 18 and the die rod 17.

A further adjustment of the die rod is accomplished by providing a set-screw 31 which extends through a threaded aperture in the yoke 23 and abuts against the casing 10 thus by manipulation of the set-screw 31 the sleeve and consequently the die may be moved toward or away from the wire driving rollers 14 and 15. For the purpose of clamping the sleeve in its final position the casing 10 is split and clamping screws 32 are provided.

The above tool or die holder constitutes part of a coil-winding machine, and it is thought that the above description is sufficient for the present purpose in showing the die holder and the means for holding a die in a given relative position in the holder.

It will be appreciated that by reason of the above-mentioned adjusting elements the position of the holder may be changed with an extremely fine degree of accuracy and that the die may be adjusted with relation to the holder.

In producing a die for application to the holder such as that shown in Fig. 1 a die rod 17 may be provided with a tip 33 consisting of a vitreous material such as glass, good results having been obtained from glass such as pyrex, it being understood, however, that various glass compositions may be employed.

The tip 33 may be secured to the die rod 17 in any suitable manner as for example, by a heat resisting cement 34. As shown in Figs. 5 and 6 a matrix 35 is provided having a die forming

recess 37, the bottom surface of which is provided with a raised portion or fin 38. The matrix is employed to receive the tip 33 when the same has been rendered plastic so that the said tip 5 will take the reverse form of the recess 37 and a die-forming cavity 39 will be produced with a coil-winding lip 41 in the proper relative position. The operation of bringing the matrix and the vitreous tip of the die blank into contact will be more clearly understood by reference to Fig. 2 which shows an apparatus comprising a holder 42 to receive a sleeve 18' which is substantially a duplicate of the sleeve 18 and in which may be disposed a die rod 17 having a vitreous die blank at one end thereof. A set-screw 21' engages a seat 22' to hold the die rod in a given position with respect to the sleeve 18' and the said sleeve is positioned in the holder 42 and secured by a set screw 43. Adjacent to the holder 10 42 is positioned a horizontal bearing bracket 44 having a bearing 45 in which a slidable holder 46 is positioned.

The holder 46 is provided with a bore 47 in which the matrix 35 is positioned. A set-screw 25 48 is provided to secure the matrix in position and the bearing bracket 44 is provided with a slot 49 to permit the set-screw 48 to travel with the slidable holder 46.

The matrix 35 is arranged with its longitudinal axis coincident with the longitudinal axis of the die rod so that a movement of the slidable holder will move the recess 37 of the matrix into contacting relation with the vitreous tip of the die rod.

For the purpose of forming the vitreous tip to the shape of the matrix, a burner nozzle 51 is provided to direct a fine needle-point flame 52 against the surface of the vitreous tip 33 to render it sufficiently plastic to take an impression.

The slidable holder 46 is actuated to move the matrix 35 by means of a hand-lever 53 having a slot 54 to receive a pivot pin 55 provided in a projection 56 integral with the slidable holder. The lever 53 is pivoted at 57 and is provided with a link 58 pivotally attached at 59 to one end of a valve arm 61 of a valve 62 controlling the gas flame 52. While the arm 53 is in its retracted or initial position the link 58 operates to direct the needle flame 52 against the vitreous die blank. As the arm 53 is moved to advance the matrix the valve 62 is closed to remove the flame and as the matrix advances to the position shown in dotted lines the softened end of the die blank is impressed with the die formation.

It will be understood that the flame 52 may not be entirely extinguished but lowered to a mere pilot light so that when the lever arm 53 returns the matrix, the flame may then issue from the nozzle 51 ready to heat another positioned die blank.

The bearing bracket 44 is provided with an adjustable stop 63 so arranged as to terminate the advance movement of the slidable holder and thus form the effective die face in a predetermined position as indicated by the arrows "X" 65 with respect to the set-screw 21'. Thus when a die has been used and has worn or does not give the proper winding, the die rod 17 may be inserted in the sleeve 18' and the end softened and a new die formed immediately.

It will be understood that although a new die rod may be employed having a new tip, it is, in many cases, only necessary to reheat the end of the vitreous tip having the die formation to renew the die form. Inasmuch as the die 70 is made in exactly the position that it is used

the new die may be readily set up in the machine without further adjustment since it occupies the exact position of the die previously employed.

It is desirable to make the matrix 35 from a die which is actually used to wind coils to a given rating data as for example a die may be made of steel or other hard material and placed in a machine to wind coils and adjusted and ground, if necessary, until it is exactly right for the winding of coiled filaments for a given wattage. This die which in Figs. 3 and 4 is designated by the numeral 64 is then forced into contact with one end of the matrix rod 35 until an impression is made as shown in Fig. 3. When the die 64 is removed, as shown in Fig. 4 the recess 37 and the fin 38 has been formed and the matrix 35 is ready to be positioned in a slidable holder 46 for movement into contact with the softened end of the die blank.

When forming the die by a movement of the matrix toward the die blank it may be preferable to heat the matrix and for this purpose a burner 65 is provided.

It will be understood that the said burner may be operated to close off as the slidable holder advances or it may be a continuous flame of relatively low temperature to maintain the matrix heated so as not to chill the die under formation. It will also be understood that if desirable the flame 52 may, after the die blank has been 100 formed, operate to supply only sufficient heat to anneal the formed die.

As hereinbefore set forth, coil-winding dies must obviously be produced of different dimensions for the manufacture of filaments for lamps 105 of different wattages. The die faces are extremely small and it is often difficult to determine by inspection the particular wattage for which the die has been made. When using a vitreous material such as glass, it is possible to take advantage of various colored glasses and use a given color glass for a given wattage die so that when a definite color has been assigned to a lamp of a given wattage the selection of the proper die is facilitated and a considerable amount of time 110 is saved.

By reason of the present invention a mandrelless coil-winding machine may be operated continuously, and in the event that a new die is required the same may be produced without 115 an appreciable amount of delay.

Fig. 9 shows a perspective view on an enlarged scale of a coil-winding die such as employed in connection with the present invention and it will be noted that this die includes a lip 41 and a cavity 120 39. The wire 16 is driven into the cavity and issues in the form of a series of convolutions in the form of a helix, the turns of which are separated by the lip 41 which determines the pitch.

It will be appreciated that inasmuch as the 125 entire action with respect to the wire and the die is a sliding or frictional engagement, it is desirable in order to avoid wear to provide a die with an extremely smooth effective surface. When employing a vitreous material such as glass or enamel composition, it is possible to provide an effective winding surface having an unbroken layer or skin and when using fusible material the skin or surface layer is extremely hard and wear resistant. Heretofore in the manufacture of 130 a diamond die for example, a reasonably smooth surface was attainable but owing to the grinding operation the cross-graining of the material became exposed and offered a certain amount of frictional opposition to the passage of the wire 135 thereover and caused wear.

In the case of a metallic die which is ground, the same result would occur. When forming a metallic die by pressure, it is not possible to get the glazed smooth layer since the surface of the metal is comparatively rough and remains so whether the die is formed by pressure or by grinding. When forming a die for the present purpose of a vitreous material a new article is produced in that it provides a coil-bending element having the desirable continuous glazed or slippery surface giving the desirable wear-resisting property which, in conjunction with the fact that the said dies may be made at a more rapid rate than dies heretofore produced, makes the present invention a decided advance step in the art of coil winding.

Although a preferred embodiment of the invention is shown and described herein it is to be understood that modifications may be made therein without departing from the spirit and scope of the invention as set forth in the appended claims. 80

What is claimed is:

1. A die for helically winding lamp filaments comprising a rod having one end tipped with vitreous material having a coiling-winding cavity. 85
2. A die for helically winding lamp filaments comprising a vitreous body having a cavity and a surface layer comprising an unbroken surface film.
